UNITED STATES PATENT OFFICE

JOHN W. DYAR, OF DETROIT, MICHIGAN

BOILER FURNACE

Application filed April 27, 1925. Serial No. 28,239.

The invention relates to steam or hot water boilers such as are used for heating purposes in buildings. It is necessary that boilers of this type be manufactured in a large number of sizes having different ratings in order to be suitable for different size houses requiring more or less radiation surface. The manufacturers have therefore been obliged to supply boilers of varying sizes and capacities, thus necessitating the manufacturing of a large number of different parts. This is a large item of expense, for the manufacturer must have at all times a sufficient quantity of each of the parts to enable any of the models to be assembled when in demand, and in addition to the initial expense of providing patterns for the large number of parts it also requires storage space because of the large number of different units which must be kept in warehouses.

Certain manufacturers have adopted a system of supplying the same fire pot and combustion chamber for three different boilers having different ratings, the smallest size boiler being converted into the larger sizes by adding additional units provided with indirect heating surface that is to say, heating surface not in direct contact with the fire. With such constructions, however, the efficiency of the boilers with the different ratings is not the same and if the boiler shows good evaporation where provided with the maximum amount of indirect heating surface it will be very much poorer when the minimum amount is used. Furthermore, from practical considerations the number of variations is limited to three and for other capacities it is necessary to supply new fire pot castings.

My invention deals with an improved boiler construction whereby a large number of different size boilers may be obtained with the use of a minimum number of standardized parts.

One of the objects is to provide a variable capacity boiler adapted to have added thereto additional boiler sections having direct heating surface, that is, surface which is exposed to the combustion gases in the fire pot.

Another object is to provide a construction

permitting the addition of auxiliary units in order to increase the size of the fire pot for the larger sizes. Still another object is to provide an annular boiler having a down-draft flue so arranged as to present indirect heating surface which may also be increased in area by the addition of auxiliary sections.

A further object is to provide a boiler having a central annular boiler section and a surrounding annular boiler section forming therebetween a down-draft flue, and to provide in such a construction means for gaining access to the flues for cleaning purposes.

A further object is to provide a boiler so constructed that a maximum draft through the chimney may be obtained while starting the fire, said boiler being provided with means for shutting off the draft when started, thus compelling the hot gases to travel through the less direct heating passages.

Other objects reside in the general arrangement of the combustion chamber and the indirect heating surfaces to provide an efficient boiler at all of the various ratings which may be obtained by the addition of auxiliary units thereto.

In the drawings:

Figure 1 is a front elevation of a boiler;
Figure 2 is a sectional plan view thereof;
Figure 3 is a vertical section on the line 3—3 of Figure 2;

Figure 4 is a view similar to Figure 3 where the boiler is provided with one auxiliary section;

Figure 5 is another similar view showing two auxiliary sections;

Figure 6 illustrates a boiler having three additional sections;

Figure 7 is a transverse section on the line 7—7 of Figure 3;

Figure 8 is a perspective view of the auxiliary annular boiler section;

Figure 9 is a perspective view of a segmental auxiliary boiler section;

Figure 10 is an enlarged longitudinal section illustrating a boiler having eight auxiliary sections;

Figure 11 is a longitudinal section at right angles to Figure 10 on the line 11—11 of Figure 2.

My improved type of boiler construction consists of a base or ash pit section 1 on which is mounted the annular boiler section 2 forming the fire pot and combustion chamber. 3 5 is a grate arranged between the ash pit section and the boiler section and 4 is a dome or top section arranged above the boiler section and spaced therefrom to provide a lateral passageway 5 for the combustion gases. The 10 dome is preferably supported on the nipples 6 having the tapered ends 7 and 8 pressed into engagement with the dome 4 and the annular boiler section 2, thus providing a water and steam conduit between these sections.

15 The dome 4 is also provided with the downwardly extending segmental water wall 9 which partially surrounds the annular boiler section 2 and is spaced therefrom to 20 form the down-draft flue 10 therebetween. The lower edge 11 of the segmental water wall terminates above the lower edge 12 of the boiler section 2, thus providing a lateral passageway, permitting the combustion 25 gases to pass around the segmental water wall and rise again through the up-draft flue 13 formed between the outer portion of the segmental water wall and the outer casing or jacket 14.

30 15 is a fire door arranged in the annular boiler section 2 near the top portion thereof. In order to provide access for this fire door the portions of the boiler surrounding the annular boiler section 2 are cut away as indicated in Figure 2, the outer casing 14 being segmental in shape and having the radially extending walls 16 connected by a segmental section 17 of a diameter only slightly greater than that of the annular boiler section 2, this 35 latter section having an opening therethrough in alignment with the fire door 15.

40 With the construction as above described the fuel is placed in the annular boiler section 2 and the combustion gases directly 45 heat the water in said section and then are directed downwardly through the down-draft flue 10 where the water in the segmental outer section 9 is also heated. The gases are then directed upwardly again through 50 the outermost flue 13 and are finally led to the centrally located chimney flue 18.

55 In order to provide a boiler of slightly larger capacity than the one above described, I have proposed to interpose between the annular boiler section 2 and the ash pit 1 an auxiliary ring 19, this ring being hollow to provide a water space therein and being suitably connected to the main boiler section 2 to allow a passage therebetween. The ring 60 is preferably made up as illustrated in Figure 8 and is provided with the bosses 20 having the tapered apertures therein leading to the hollow interior of the ring. There are 65 also corresponding apertured bosses on the bottom of the main boiler section 2 and the

two sections are connected together by the nipples 22 having the tapered ends 23 adapted to enter the tapering holes in the boiler sections and form a press fit with the same. For maintaining the auxiliary ring 19 in position there is preferably provided a clamping arrangement, and as illustrated this comprises the rods 24 threadedly engaging the threaded bosses 25 on the steam dome and extending downwardly in the down-draft flue 10 through the apertures 26 formed in the lugs 27 on the auxiliary ring 19. The lower end 28 of the rod is also threaded and the clamping is maintained by means of a nut 29 threaded upon said rod and engaging the undersides of the lug 27. With this construction it will appear that the depth of the fire pot is increased by the addition of the auxiliary ring 19 and also the direct heating surface is increased. The boiler constructed in this manner will therefore have a higher rating than the boiler first described.

70 75 80 85 90 95 100 105 110 115 120 125 130

In order to construct the next larger unit in the boiler series, I propose to increase the amount of indirect heating surface by adding an auxiliary segmental ring 30 to the outer segmental water wall 9. This unit is illustrated in Figure 9 and is connected to the boiler by the nipples 31 constructed similarly to the structure previously described in connection with the auxiliary ring 19. While the size of the combustion chamber and fire pot is not increased by the addition of the segmental ring 30 the path for the combustion gases is considerably lengthened by increasing the length of the down-draft flue 10 and the up-draft flue 13, and there is also provided the additional heating surface of the segmental ring 30.

lower ends with the lugs 37 upon the auxiliary segmental sections.

With the construction as thus far described, it will be apparent that in order to build a larger boiler furnace the same main parts may be used and it is only necessary to add additional units first to the main boiler section and second to the surrounding segmental water wall. Thus, the number 10 of different parts which are necessary for assembling a series of boilers having progressively increasing ratings is reduced to a minimum and as illustrated in Figure 3, there are nine different boilers which may be formed 15 from the parts shown. The first boiler of the series is that employing only the basic units as illustrated in Figure 1. The other boilers are formed by successively adding units 19, 30, 32, 33, 47, 48, 49 and 50 and by 20 properly proportioning the size of the various parts this will permit a variation in rating from 550 to 900 feet.

For starting the fire or stimulating it at any time, it is desirable to have a direct draft 25 and this is provided by forming one or more direct draft apertures 51 in the dome 4, these being preferably arranged concentric with the fire pot and combustion chamber and in alignment with the stack 18. For controlling these apertures, suitable dampers 52 are 30 provided so that when the dampers are in open position the combustion gases may pass directly to the stack through the apertures 51, but when the dampers are closed the gases 35 are forced to travel the indirect route around the depending segmental water wall.

It has already been stated that the outer casing 14 has a cut-away portion adjacent the fire door of the furnace formed by the 40 radially extending walls 16. This construction facilitates the placing of clean out doors so as to provide access for the down-draft and up-draft flues, the doors being located in the radial walls 16. These doors 45 are represented in the drawing by the numerals 53 and are hingedly connected to the radial walls 16 so that when the doors are opened a cleaning brush or scraper may be introduced into the flues. If the cleaning 50 brush is provided with a flexible handle it will permit the same to be worked around to the opposite side of the flues from the fire door and therefore, every portion of the flue surface may be cleaned from the accumulated 55 soot and dust. This is an important feature of my boiler construction for it is very essential to the efficient operation of the boiler that the flues be kept free from soot and dust and with previous annular boiler constructions 60 provided with down-draft flues there has never heretofore been any arrangement suggested permitting the cleaning of the flues.

What I claim as my invention is:—

1. In a boiler furnace, the combination with

an annular boiler section forming the fire pot and combustion chamber, of a top section extending across the upper end of said annular boiler section and connected thereto, a segmental water wall depending from the top 70 section and surrounding a portion of said annular boiler section in spaced relation thereto to form a passageway for the combustion gases, and a closure for said passageway disposed at each end of said segmental water 75 wall, said closure permitting access to said passageway for cleaning the same.

2. In a boiler furnace, the combination with an annular boiler section forming a fire pot and combustion chamber, of a top section extending across the upper end of said annular boiler section and outwardly beyond the same, said top section being spaced from and connected to said annular section, a segmental water wall depending from the top section 80 and surrounding said boiler section in spaced relation to define a down-draft flue, an outer segmental jacket surrounding said water wall in spaced relation to form an up-draft flue, and closure means for said down-draft 85 and up-draft flues disposed at each end of said segmental water wall and jacket, said closure means permitting access to said down-draft and up-draft flues for cleaning the same. 90

3. In a boiler furnace, the combination with an annular boiler section forming the fire pot and combustion chamber and provided with a fuel door opening therethrough, of a top section extending across the space 100 within said annular section and radially outward beyond the same, said top section being spaced from and connected with said annular section, a segmental water wall depending from the outer edge of said top section 105 surrounding a portion of said annular section and forming a down-draft flue, said segmental water wall terminating at opposite sides of said fuel door opening, and a segmental jacket surrounding said water wall 110 and also terminating at opposite sides of said fuel door opening forming an up-flue in communication with said down-flue, the segmental formation of said water wall and jacket permitting of the introduction of fuel 115 through the fuel door opening.

4. In a boiler furnace, the combination of an annular boiler section forming the fire pot and combustion chamber and provided with a fuel door opening therethrough, of a segmental water wall surrounding a portion of said annular section on opposite sides of the fuel door opening, a segmental jacket surrounding said segmental water wall and a removable closure at the end of said segments 120 for providing clean out openings to the space between said annular section and water wall and between the latter and said jacket. 125

5. In a boiler furnace, the combination of an annular boiler section forming the fire pot 130

and combustion chamber and provided with a fuel door opening therethrough, a steam dome above said boiler section and spaced therefrom, a segmental water wall depending from said steam dome and surrounding a portion of said boiler section forming a segmental down-draft flue, an outer segmental jacket surrounding said water wall and forming a segmental up-draft flue, a wall extending transversely of said segmental jacket for closing the ends of said segmental flues, and a clean out door in said wall for permitting access to said flues.

6. In a boiler furnace, the combination with an annular boiler section forming the wall of the fire pot and combustion chamber, of a steam dome spaced above and connected to said boiler section, an annular segmental water wall depending from said steam dome and surrounding said fire pot, an additional separately formed annular boiler section forming an extension of the wall of said fire pot thereby increasing the coal capacity thereof, an additional segmental boiler section secured to said segmental water wall to form a continuation of the same, and nipples connecting the respective additional sections to said fire pot and said water wall respectively.

7. In a boiler furnace, the combination with an ash pit section, a grate, an annular fire pot formed of a plurality of hollow walled boiler sections superposed one upon the other, a steam dome spaced above said fire pot, a segmental water wall depending from said dome and surrounding said annular fire pot forming a down-draft flue, and an annular segmental jacket surrounding said water wall forming an up-draft flue, one of said hollow walled boiler sections being of a height adapted to form a fire pot and another of said sections being of a lesser height and adapted to increase the depth of said fire pot to form a furnace of higher rating, and an additional segmental boiler section connected to said depending water wall to increase the amount of radiation surface exposed to said down-draft and up-draft flues.

8. In a boiler furnace, the combination with a boiler section forming the fire pot and combustion chamber, said boiler section being provided with a fuel door opening therethrough, of a top section extending across the upper end of said boiler section and radially outward beyond the same, said top section being spaced from and connected with said boiler section, a segmental water wall connected to said top section and surrounding a portion of said boiler section and cooperating therewith in the formation of a passage for the combustion gases, said segmental water wall terminating at opposite sides of said fuel door opening whereby to permit of access thereto.

9. In a boiler furnace, the combination with a boiler section forming the fire pot

and combustion chamber, of a steam dome spaced above and connected to said boiler section and an annular segmental water wall depending from and connected to said steam dome and partially surrounding said boiler section forming a down-draft flue passage, said segmental water wall forming an opening permitting access to said fire pot for fueling the same and a removable closure at said end portions of said segmental wall forming a clean-out opening for said flue passage.

10. In a boiler furnace the combination with an annular boiler section forming the wall of the fire pot and combustion chamber, of a steam dome spaced above and connected to said boiler section, an additional separately formed annular boiler section forming an extension of the wall of said fire pot thereby increasing the coal capacity thereof, nipples connecting said additional section with the first mentioned section affording communication of the boiler fluid between said sections, and an annular segmental water wall connected to said steam dome above said boiler section and spaced therefrom, said segmental water wall forming an opening permitting access to said fire pot for fueling the same.

In testimony whereof I affix my signature. 95
JOHN W. DYAR.
